(57) CLAIM

The ornamental design for a versatile art display, as shown and described.

DESCRIPTION

FIG. 1 is an isometric view of a versatile art display in a folded position, the versatile art display having a triangular shape; FIG. 2 is a left side view of the triangular shaped versatile art display in the folded position, which is a mirror image of the right side view (not shown);

FIG. 3 is a front view of the triangular shaped versatile art display in the folded position;

FIG. 4 is back view of the triangular shaped versatile art display in the folded position;

FIG. 5 is a top view of the triangular shaped versatile art display in the folded position;

FIG. 6 is a bottom view of the triangular shaped versatile art display in the folded position; and,

FIG. 7 is a top plan view of the triangular shaped versatile art display in an unfolded position.

The broken lines in FIG. 7 illustrate scored portions of the versatile art display in the unfolded position, and form part of the claimed design.
